J. R. O'NEILL,
LABEL APPLYING MACHINE,
APPLICATION FILED OCT. 31, 1912. RENEWED AUG. 16, 1918.
1,300,639.

Patented Apr. 15, 1919.

UNITED STATES PATENT OFFICE.

JOHN R. O'NEILL, OF RIDGEWOOD, NEW JERSEY.

LABEL-APPLYING MACHINE.

1,300,639.

Specification of Letters Patent. Patented Apr. 15, 1919.

Application filed October 31, 1912, Serial No. 728,765. Renewed August 16, 1918. Serial No. 250,234.

To all whom it may concern:

Be it known that I, JOHN R. O'NEILL, a citizen of the United States, residing in Ridgewood, county of Bergen, and State of New Jersey, have invented certain new and useful Improvements in Label-Applying Machines, of which the following is a specification.

This invention relates to apparatus for applying labels or sealing strips to boxes, bundles or analogous articles, and has for its object to provide a device of the character described which will apply the middle portion of a label or sealing strip to one end or face of a box or package, and simultaneously therewith fold the ends of the strip against the bottom and top, or other adjacent faces of the box or package.

A further object of the invention is to provide a device of the character described in which the operation of a single crank or lever feeds out the gummed strip, applies moisture to its gummed surface and cuts off a predetermined length of the strip, the cut off portion being properly positioned with regard to the applying device so as to be applied to the box or package without being handled by the operator.

A further object of the invention is to provide a device of the character described which may be adjusted for boxes of various sizes and relative dimensions, and in which the operation of a single adjusting device effects the adjustment not only of the applying devices but also the strip feeding and cutting devices to correspond.

With the above objects in view, my invention consists in the mechanism herein-after described and shown in the accompanying drawing forming part of the specification, it being understood however that the invention is not limited to the details of such mechanism, but that the same may be widely varied without departing from the spirit of my invention or the scope of the appended claims.

In the said drawings Figure 1 is a vertical section through the entire apparatus.

Fig. 2 is a horizontal section through the inclosed base immediately beneath the top wall thereof.

Figs. 3, 4 and 5 are detail views which will be hereinafter described.

Referring now to the drawings, and par-

ticularly Fig. 1 thereof, 1 represents the base of my improved apparatus to the upper surface of which is attached a pair of uprights 2, one only of which is shown, connected by a cross bar 3, and forming guide-ways for the cross head 4 mounted for vertical movement thereon. Projecting laterally from the cross head 4 at the ends thereof, are two arms, one of which is shown at 5, extending over the base portion 1 and connected at their free ends by a transverse plate 6 integral therewith and rigidly connected thereto. For vertically adjusting the cross head 4 a screw 7 is provided which is threaded through the cross head and seated at its lower end in a socket bearing 8 on the upper surface of the base 1. A bevel gear wheel 9 is attached to the screw 7 near its lower end and meshing with this gear is a similar gear 10 attached to the end of a screw shaft 11 rotatably mounted in the cross bar 12 attached to the rear edges of the uprights 2. The screw shaft 11 is threaded into a lug 13 which projects upwardly at the rear edge of a horizontal slide 14 mounted in guide ways in the uprights 2 above the base 1 and provided at its forward edge with a vertical plate 15 of a width such as to enable it to project between the side arms 5.

Immediately beneath the slide 14 a plate 16 is mounted on springs 17 seated on the upper surface of the base 1, suitable bolts 18 being provided for holding the plates 16 in light contact with the under surface of the slide 14. The plate 6 projects beyond the front edge of the plate 16 and formed in the projecting end of the plate 6 in alinement with the edge of the plate 16 is an orifice 19 adapted to form a guide for the end of the gummed label strip 20, which is fed upward from the base of the machine, immediately in front of the plate 16 as will be presently described.

The plates 6, 15 and 16 as above described, form a pocket for the reception on the end of the box or package when the label strip is applied thereto, the box being thrust between the plates 6 and 16 by the operator, and into contact with the plate 15. To cause the label strip to tightly adhere to the box or package, it is necessary for its gummed surface to be pressed firmly against the surface of the box or package. To this end the

plate 16 is supported on springs in the manner described, the plate 6 being adjusted to a position such that its distance from the plate 16 is slightly less than the depth of the box. To effect this adjustment the screw 7 is provided with a hand wheel 21 by means of which the screw may be turned in either direction to raise or lower the cross head 4, carrying the plate 6. The plate 15 is positioned back of the edge of the plate 16 a sufficient distance to permit the entire length of the projecting ends of the label strip 20 to be pressed against the surface of a box by the plates 6 and 16. In most cases the greater the depth of the box the greater the length of the ends of the strip which are applied to the top and bottom faces to secure a proper sealing of the box, and therefore, the adjusting screw of the plate 15, is connected to the screw 7 by gears 10 and 12 so as to be adjusted in synchronism with the plate 6 by the operation of the hand wheel. To permit however of the separate adjustment of the plates 15 and 16, for boxes or packages of unusual dimensions, as large thin boxes or small deep boxes, I have mounted the screw 7 so that it may be slightly lifted to disconnect the gears 9 and 10. To facilitate the lifting of the screw 7, it is provided at its bearing in the cross bar 3 with a circumferential groove 22 in which is fitted an eccentric cam 23 carried by a spindle 24 having a flat head to facilitate its manual operation.

The gummed strip 20 is preferably supplied in the form of a roll 25 which is mounted on a spindle 26 within the base 1. From the roll 25 the strip extends through suitable feed rollers 27 and 28, thence over the stationary blade 29 of the shears and through the feed rollers 30, 31. From these rollers the strip passes between the moisture applying rollers 32, 33 and thence beneath the guide roller 34 through a curved guide 35 which directs the strip upwardly between the rollers 36, 37 and thence across the face of the label applying pocket formed by the members 6, 15 and 16.

For actuating the feed rollers to feed the labels in the manner described, a handle or crank arm 40 is provided, the same being mounted on a stub-shaft 41 rotatable in a suitable journal in the side of the base 1. Upon the inner end of the shaft 41 a bevelled gear 42 is attached which meshes with a similar gear attached to a longitudinal shaft 43 extending along the side of the base 1. This shaft 43 is slidably mounted in its bearings and on its front end is attached a friction roller 44 which engages the face of the friction disk 45 loosely mounted on a stub-shaft adjacent the feed roller 36, as shown in Fig. 2. The edge of the disk 45 is provided with gear teeth which mesh with a gear 49 loose on the shaft of the roller 36

and driving, through a multiplying train, a gear 49^a fast to the shaft. Attached to the shaft of the roller 36 adjacent the disk 45 is a small belt pulley 46 which carries a belt 47 leading to a similar pulley 48 attached to the shaft of the feed roll 30.

Coöperating with the fixed blade 29 of the cutting mechanism is a pivoted blade 50 (see Fig. 3) which is actuated by spring 51 at proper intervals as will now be described, to cut off a sufficient length of the tape for application to the box. The blade 50 is provided with a lateral extension 52 beyond its pivotal support, and coöperating with this projection is a cam 53 carried by the longitudinal shaft 43. The cam 53 (see Fig. 4) is connected to the shaft 43 by means of a spiral groove 54 in the shaft into which fits a pin carried by the cam. The shaft is provided with bearings on each side of the cam 53 so that the cam will be held against longitudinal movement with the shaft, and will be turned on the shaft when the shaft is so moved to thereby adjust the position of its operating shoulder 54^a.

For actuating the feed roller 27 I provide an arm 55 rotatably mounted on a shaft of the roller 27 as shown in Fig. 5 and carrying a pawl 56 which engages a ratchet formed on the end of the feed roller. A link 57 is connected to the arm 55 and attached by a pin to the face of the gear 42 on the shaft 41 of the handle 40. For adjusting the shaft 43 longitudinally of the base 1, levers engaging a collar attached to the shaft are provided, the said levers being attached to a shaft 60 projecting through the wall of the base 1 and provided with a handle 61 for its manual adjustment. The shaft 60 is also provided with a sprocket wheel 62 carrying a chain meshing with a wheel on the shaft of a chain 63 detachably connected to the slide 14 by a pin 64 as shown in Fig. 1.

The operation of the apparatus will now be described. The label applying pocket is first adjusted by means of a hand wheel 21 to the proper size for the boxes to be labeled or sealed, and in such adjustment the shaft 43 carrying the roller 44 is moved longitudinally to vary the gear ratio of the operating handle 40 and the feed rollers, and consequently the length of the strip fed at each revolution of the handle 40. As a larger box obviously requires a longer sealing strip and vice versa, a single adjustment of all the parts by the hand wheel 21 is usually sufficient to properly set all parts for the different sizes of boxes, but in cases of boxes of unusual relative proportions, the friction gears may be adjusted separately from the strip applying pocket by means of the handle 61, the pin 64 being for this purpose lifted out of its socket attached to the chain 63. The longitudinal adjustment of the shaft 43

also alters the position of the cam 53 on the shaft so that the time of operation of the knife in the cycle of operation effected by a single complete revolution of the handle 40 is varied according to the length of the strip fed by the feed rollers. This adjustment is necessary for the reason that the length of the strip depending below the surface of the plate 16 when the box is thrust into the pocket must be equal to the length of the portion of the strip projecting above the plate 6.

The size of the feed rollers is such that when the machine is properly adjusted, one revolution of the handle 40 feeds out sufficient length of strip for the box to be labeled, and it will be noted that the feed rollers 27, 28 will be actuated only during the first half of each revolution. This operation of these feed rollers is merely sufficient to feed the end of the strip between the shear blades and into the bight of the continuously operating rollers 30, 31. After the rollers 30, 31 take hold of the strip it is drawn through the rollers 27, 28 the ratchet mechanism of these rollers permitting them to overrun the actuating pawl, but when the shears are operated as described to sever the strip, the rollers 27, 28 will cease operating whereas the cut off portions of the strip will be fed inward by the rollers 30, 31, 36, 37 into position to be engaged by the box when thrust into the applying pocket. The purpose of this construction is to leave the free end of the strip always out of contact with the moisture applying rolls 32, 33. When the strip is left in contact with these rolls and the machine left stationary for any appreciable length of time, the gummed surface of the strip will adhere to the roll so that in starting up again it is necessary to clean and rethread the machine.

Having thus described my invention, what

I claim and desire to secure by Letters Patent is:—

45

1. In a machine of the character described, the combination of means for applying a label to boxes or packages of various sizes, adjustable means for severing such label from the end of a web and feeding the same 50 into juxtaposition to said applying means, and means for simultaneously adjusting said applying means and said feeding means.

2. In a machine of the character described, a label applying pocket having three sides, 55 two of said sides being adjustable, means for simultaneously adjusting said last mentioned sides, and means for separately adjusting said sides.

3. In a machine of the class described, a 60 label applying device comprising two substantially parallel members, one of said members being yieldingly mounted, a transverse member, means for simultaneously adjusting one of said parallel members and said trans- 65 verse member, and means for separately adjusting said members.

4. In a machine of the character described, the combination of means for supplying, in the path of a box or package to be sealed, 70 adhesive labels or strips of various lengths, means adapted to press against and affix the labels or strips of tape to a box or package, and means operatively connected with the said label supplying means and pressing 75 means whereby the two latter may be adjusted simultaneously to accommodate boxes or packages of various sizes.

In testimony whereof, I have hereunto set my hand at the city, county and State of 80 New York, this 26th day of October, 1912.

JOHN R. O'NEILL.
